SPINAL APPLIANCE

Ransom J. Barrows, Jamestown, N. Y.

Application February 17, 1932. Serial No. 593,641

7 Claims. (Cl. 2—44)

This invention relates to a spinal appliance, body brace or supporting device designed to relieve or eliminate body ailments such as spinal curvature, spinal weakness and deformities and other spinal mal-conditions.

A primary object or purpose of the invention is to produce an appliance or device, as shown, which by reason of its construction gives proper body support when worn by a person having a weak back or other spinal trouble and serves as an aid in regaining normal health and strength and also through an extension or lifting support to that portion of a person's body above the hips tends to straighten spinal deformities or to overcome any spinal mal-condition.

Another important object is to provide an appliance of the present character well adapted to be made up and fitted according to individual cases and which employs a supporting corset with back stays to which shoulder straps and abdominal straps are connected.

Other objects of this invention will appear from a consideration of the following description, taken in connection with the drawings which form a part thereof, in which Figure 1 is a front, inside, full development of the spinal appliance; Figure 2 is a sectional view of the back-stay, taken on line 2—2 of Figure 1 and looking in the direction of the arrows; Figure 3 is a front view of the appliance and Figure 4 is a back view of the appliance as worn; Figure 5 is an enlarged fragmentary perspective view of one of the detachable back-stays and the associated parts.

Referring specifically to the drawings, 6 designates a spinal appliance comprising a corset body or part 7 made in two substantially similar sections 7' each having flexible or firm stays 8 of steel or other material inserted between or fastened on layers of cloth or other material, the ends of these stays optionally having protecting caps 9 or other material or padding 10 to prevent said ends from wearing through the coverings 11 at the top and bottom of the corset edges. These corset stays 8 are held in position by means of sewing or otherwise as at 12. The upper and lower edges of this corset-part are covered with a soft wool, felt or other padding 13 as shown in Figures 3 and 4, and then covered with the aforesaid webbing, cloth, or other material 11, also sewed or fastened around the edges of the corset or body part 7. Those portions of the appliance disposable underneath the arms of the wearer, are further covered with shields 14 to protect against the effect of perspiration.

As best seen in Figures 1, 3 and 4, a gusset,

recess, or loose part 15 is inserted or fitted for the disposition over the hips of the wearer, or the corset part is so made as to be form-fitting as the needs of the particular case may indicate.

The front of the corset has straps of webbing 16 or other material secured to one section 7' and coacting buckles 17 secured to the other section 7' for fastening and adjustment. Optionally this front fastening can be effected by means of eyelets and laces or in any other manner.

A novel abdominal pad 18 is employed, being made in various sizes and shapes and of heavy canvas or other material 19 with or without stays, usually covered with cloth 20 and bound by silk braid or other material 21. Buckles 26 permitting of adjustment, are attached to said pad to which are fastened the straps of webbing or other material 22, 23, 24 and 25 to pass around the body. These strap ends 22, 23, 24 and 25 are affixed to the back stays as best shown in Figure 1, 2 and 5, with the opposite ends interlaced into said buckles 26 for adjustment so that the pad will give a lifting support to the abdominal region, in connection with the appliance, and also, hold the lower ends of the back stays closely against the body of the wearer.

Said back stays are an important feature and comprise two main stays of steel 28 or of other flexible or firm material shaped to conform to the shape of the body. Stays 28 and adjoining stays 29 are covered on both sides by strips of strong silk-finished webbing or other material 27 and 27A. Said center stays 28 are longer than the stays 29 which are fastened to the sections 7' of the corset part. The coverings of said stays 28 have eyelets 30 inserted along each edge for the purpose of receiving laces 31 which serve to connect the two main back stays and for the purpose of attaching the corset parts 7' in a manner to allow of making certain adjustments. The two center stays 28 are usually fastened together by lacing as above but this, as well as the attachment of the corset parts 7' to the back stays 28, can be done in other manner. When the appliance is fitted to the body of the wearer, such stays 28 rest on opposite sides of the spinal column.

Shoulder straps 32 of elastic webbing or other material with soft padding 33 affixed, are fastened to the top of back stays 28, as shown particularly in Figure 5, by a swivel plate 37 or movable attachment and center rivets 34, the other ends of straps 32 being interlaced into buckles 35 attached to the back stays 28 as shown at 36 to permit of adjustment.

As best seen in Figure 5, rivets 34 at top of the back stays 28 extend through the adjacent webbing covering, stay, and swivel plate 37, and at the bottom of the stay through the covering 5 and straps to hold them closely together and firmly to the backstays 28.

The broken away part of covering 27A discloses strips 36, by which the shoulder strap buckles 35 are attached, strap 32 being released 10 from the buckle shown.

It will be realized that the back stay parts made up of the stays 28 and their coverings are detachable and adjustably connected together and to the corset sections 7' and that the shoulder straps 32 and straps 22, 23, 24 and 25, are attached solely thereto. The fact that the back stays 28 are detachable from the corset sections 7' permits of various sizes and shapes of corset sections to be accommodated.

20 It will be realized that the present combination of elements gives an extension or lifting support to carry the weight of the upper portion of a person's body and to overcome downward pressure along the spine, and in the same manner 25 to exert a tendency in the direction of correction of any spinal deformity or deflection and for the benefit or elimination of any spinal mal-condition. These results are due to the coaction of the form-fitting corset part closely held 30 against the body and coming well up under the arms of the wearer, together with the supporting effect of the backstays along the spinal column and in combination with the straps for support of the shoulders and the pad and straps for 35 the support of the abdomen.

The embodiments of this invention have been shown and described by way of example only and it is to be understood that various changes may be made without departing from the spirit and 40 scope of the following claims.

I claim as my invention:—

1. A spinal appliance consisting of a corset-like body having back stay means extending below the body proper, an abdominal pad below 45 the body, strap means connected to said stay means below the lower edge of the body proper, strap means connected to said stay means above the lower edge of the body proper, each of said strap means supporting said pad.
- 50 2. A spinal appliance consisting of back stay members adjustably connected together; a corset-like body having sections detachably connected

to said members, an abdominal pad, and supporting straps for said pad connected to said members.

3. A spinal appliance consisting of back stay members adjustably connected together; a corset-like body having sections connected to said members, an abdominal pad, and supporting straps for said pad connected to said members, above and below the lower edges of the body, and shoulder straps connected to said members.

4.. A spinal appliance consisting of parallel back stay members, a lacing securing said members together, a corset-like body with staying for support, lacings for attaching and adjusting said body on said members, an abdominal pad, said members extending below the body part, supporting straps connected to the members below said body and to the pad and supporting straps connected to the members above the lower edge of the body and to the pad.

5. A spinal appliance consisting of parallel back stay members, a lacing securing said members together, a corset-like body, lacings securing said body to said members, an abdominal pad, said members extending below said body, supporting 100 straps connected to the members below the said body and to the pad and supporting straps connected to the members above the lower edge of the body and to the pad, shoulder straps extending from the members, and adjustable connections 105 between the members and the free ends of the straps.

6. A spinal appliance consisting of a pair of parallel stay members, a lacing connecting said members, an abdominal pad with supporting 110 straps for said pad extending from said members, shoulder straps extending from said members, means to adjustably secure the free ends of the shoulder straps to said members, a corset-like body, and means detachably connecting said body 115 to said members.

7. A spinal appliance consisting of a corset-like part completely encircling the body, an abdominal supporter adjacent the front lower end of said part, straps connected to the lower portion of said part relatively close to the rear median line thereof, adjustable supporting connections between said straps and supporter, shoulder straps, back stay means, and means to adjustably secure the free ends of the shoulder straps to the 125 back stay means.
